(57) **CLAIM**

The ornamental design for a solar light with rectangular solar collector, as shown and described.

DESCRIPTION

FIG. 1 is a perspective view of the solar light with rectangular solar collector showing the present invention;

FIG. 2 is a front view of the solar light of FIG. 1.

FIG. 3 is a left side view of the solar light of FIG. 1.

FIG. 4 is a right side view of the solar light of FIG. 1.

FIG. 5 is a back view of the solar light of FIG. 1.

FIG. 6 is a top view of the solar light of FIG. 1; and,

FIG. 7 is a bottom view of the solar light of FIG. 1.

The broken lines shown on the drawings are for illustrative purposes only and form no part of the claimed design.
